SHEDERICK J. LOWE, OF QUINCY, ILLINOIS.

Letters Patent No. 71,515, dated November 26, 1867.

IMPROVED LAMP FOR KINDLING FIRES.

The Schedule referred to in these Letters Patent and making part of the same.

TO ALL WHOM IT MAY CONCERN:

Be it known that I, SHEDERICK J. LOWE, of Quincy, Adams county, State of Illinois, have invented certain new and useful Improvements in Fire-Kindling Lamps; and I do hereby declare the following description and accompanying drawings are sufficient to enable any person skilled in the art or science to which it most nearly appertains to make and use my said invention or improvements without further invention or experiment.

The nature of my invention and improvements consists in providing a lamp with a traversing-wick tube, made adjustable that it may be moved in and out when required; and in making said traversing adjustable wick-tube bent or curved that it may be moved in and out to vary the position of the burning end of the wick; and in a case fastened to the oil-vessel, to hold and guide the wick-tube; and in certain devices to hold the wick-tube as desired; and in a shield or guard-plate, arranged in front of the oil-vessel, to keep the heat of the fire kindled from heating the oil-vessel; also in a partition in the oil-vessel to hold back the oil when the lamp is tipped, and prevent it from running to the wick so freely as it would do if there were no partition. In the accompanying drawings—

Figure 1 is a plan or top view of a lamp with my improvements.

Figure 2 is a section on the line $z z$ of fig. 1.

In these drawings, A is the oil-vessel, which may be made in the form shown, or in such other form as will answer the purpose, and provided with a screw-cap, B, through which it may be filled with oil, which screw-cap has a small hole in its apex to let in the air as the oil is exhausted by being burnt. I make a long slot in the top of the vessel A, and fasten the case C of the wick-tube H in said slot, which case C is curved, as shown in fig. 2 of the drawings. I brace the case C by the bracket F, and fasten the handle G to the vessel A and case C. I make a serpentine wick-tube, H, in the form of a *cyama-reversa*, about three inches wide, and one-eighth of an inch deep, and fit one end to slide and traverse in through the case C nearly or quite to the vessel A, so that it may be slipped out, to light a fire, to the position shown in dotted lines H', when the end of the wick-tube will be as low as the bottom of the vessel A, to light the fire to be kindled. After the fire is kindled it may be pushed back, so that the outer end of the wick-tube will be higher than the top of the oil-vessel, so as to prevent the oil from running to waste. This wick-tube is provided with one or more slots, I, to insert a pin, and adjust the wick. I fasten the knob J to the top of the tube H, by which knob the tube may be traversed, and, when pushed back, may be held by the ring K hinged on the case C, so that it may be laid over the knob to hold the tube in. The plate L is hinged to the case C, and has a slot, M, in it, in which the knob J traverses, and stops the knob when the tube is slid out for use. The upper part of the slot M is made so wide that the plate L may be turned back off of the knob when it is desirable to take the tube H out to put in a new wick.

Figure 3 is an extinguisher, which may be applied to the wick-tube to put out the light.

This extinguisher has the pointed wire N fastened to it to pick up or adjust the lamp-wick R.

I put a partition, P, across the vessel A, and make one or more small holes through it at the bottom for the oil to pass through slowly. This partition holds a part of the oil back when the lamp is tipped, and prevents it from pressing on and running through the wick so fast as it might otherwise do.

To prevent the fire kindled from heating the oil-vessel A, I apply a guard or shield-plate, Q, and arrange a little distance in front of the vessel, as shown in the drawings, and fasten the ends to the vessel A, and the top to the case C. This plate prevents the rays of heat from the fire from coming in contact with the oil-vessel.

To use this lamp to kindle a fire, light the wick and run out the tube, and apply it to the wood or materials to be kindled until they begin to burn, when the lamp may be taken away, and the tube run in and fastened by the ring K.

Having described my improvements—

1. I claim a lamp, provided with a traversing adjustable wick-tube that may be moved or slid in and out when required.
2. I claim making the traversing adjustable wick-tube of a lamp curved, substantially as described for the purposes set forth.

3. In combination with the oil-vessel, I claim the case C for holding and guiding the wick-tube, substantially as described.

4. In combination with the traversing-wick tube, I claim the hinged slotted plate L and ring K for holding the wick-tube, as described.

5. I claim, in combination with the oil-vessel, the shield or guard-plate Q, arranged in front to keep the heat of the fire kindled from heating the oil-vessel.

6. I claim the partition in the oil-vessel to hold the oil back when the lamp is tipped, and prevent it from running to the wick so freely as it would do if there were no partition.

SHEDERICK J. LOWE.
